UNITED STATES PATENT OFFICE.

PHILIP C. STINGEL, OF STONEHAM, MASSACHUSETTS.

INNER SOLE FOR SHOES.

Application filed September 12, 1925. Serial No. 55,921.

The invention relates to an improvement in inner soles for shoes in which the inner sole is provided at the heel portion with a shock-absorbing pad having a shell backing 5 of metal or other hard substance and a wrapping or covering of some flexible material passed over the upper surface of the pad and around the adjacent marginal edges of the inner sole and fastened to the under 10 side thereof.

The object of the invention is to improve the pad, the shell and the cover both structurally and in point of operative efficiency.

The invention can best be seen and understood by reference to the drawings, in which—

Figure 1 is a plan of the improved inner sole.

Fig. 2 is a plan of the heel portion of the 20 inner sole with the shock-absorbing pad, shell and cover removed.

Fig. 3 is a section on the line 3—3 of Fig. 2.

Fig. 4 is a section on the line 4—4 of 25 Fig. 1.

Fig. 5 is a section on the line 5—5 of Fig. 1.

Fig. 6 is an elevation of the front edge or breast of the shell.

Fig. 7 is a longitudinal cross section of the 30 combined parts at the heel of the inner sole showing a modified method of attaching the heel from that shown in Fig. 4.

Fig. 8 is a plan of the shock-absorbing 35 pad.

Fig. 9 is a section on the line 9—9 of Fig. 8.

Fig. 10 is a plan of the shell backing the pad.

Fig. 11 is a section on the line 11—11 of 40 Fig. 10, and

Fig. 12 is a longitudinal cross section of the combined shock-absorbing pad and shell backing the pad.

Fig. 13 is a plan of the cover before its 45 application to the inner sole and associated parts.

Referring to the drawings:—

1 represents the inner sole, 2 the shock-absorbing pad, 3 the shell backing the pad and 4 the cover.

The inner sole is dished at its heel portion 5. The shell with pad fitting therein and attached thereto, fits within the dished portion of the sole to which it is preferably cemented, while the cover extends over the top

surface of the pad and around the marginal edges of the pad, shell and sole and is fastened to the under side of the sole.

The shell 3 into which the pad fits in 60 general contour is quite similar to the dished portion of the sole into which it fits. The inclined body, however, of the shell is provided along its sides and back with a flattened, outturned marginal edge 6 which presents substantially horizontal under and top surfaces 7 and 8, respectively. The edge 9 of the heel portion of the sole at the sides and back fits beneath the under surface 7 of the outturned marginal edge 6 of the shell, 70 while the top surface 8 thereof provides a bearing for a marginal edge portion of the pad, as will later be explained.

In longitudinal dimension the shell has an extension substantially equal to an attached heel 10, as illustrated in Fig. 4, or at least such extension as will enable all of the nails 11, by which the heel is attached to the inner sole, to strike the backing when the nails are driven. It has a rounding back 80 edge with substantially straight side edges following the general plan of the attached heel. The forward edge or breast 12 of the shell is depressed and has a slight curvature as shown in Fig. 6, while the front corner 85 edges 13, 13 thereof are turned down to lie substantially flat so as to present no sharp upturned edges at these points.

The dishing or concavity of the body of the shell is such that it will have along its 90 sides and back substantially the same angular inclination at points equidistant from its side and back edges, thus enabling all heel nails along the sides and back of the heel when driven simultaneously to strike 95 the shell at the same time.

The shell backing the pad is used both in connection with heels attached to the inner sole by nails driven from the outside, as shown in Fig. 4, or from the inside, as 100 shown in Fig. 7. When used with nails driven from the outside or those which strike the shell and are deflected by it, the shell is made of tempered steel in order that the shell may assume its normal shape when 105 distorted by pressure incident to various operations in connection with the making of the shoe. When the shell is used with nails driven from the inside and which must pass through the shell, the shell is made of any 110 suitable hard material of fibre, permitting of the nails being driven through it but of

such flexible or elastic material as will permit the shell to resume its normal shape when distorted the same as when the shell is made of tempered steel.

5 The shock-absorbing pad 2 is made of rubber or a resilient composition capable of being moulded and vulcanized. The moulded structure of the pad bears a certain determinate relation in various parts to its shell 10 backing. In this connection attention is first directed to that marginal edge portion 15 of the pad along its sides and back. This portion of the pad has a bearing to rest upon the top surface 8 of the flattened, outturned 15 marginal edge 6 of the shell and is made of sufficient thickness to cover and provide a cushion around the top edge of the shell. The pad extends forward over the front or breast portion of the shell, gradually growing 20 thinner until the forward edge thereof blends with the top surface of the inner sole along the shank.

That portion 16 of the pad which lies above the forward edge 12 of the shell is 25 made of considerable thickness in order that the edge of the shell shall not be felt when pressure is applied to the pad at this point. Such thickness in the pad above the forward 30 edge of the shell is obtained on account of the relative depression of the shell along its forward edge and by the depression of the front corner edges of the shell as previously explained.

The forward end portion 17 of the pad is 35 a narrowing portion, the sides thereof converging. This enables the pad to be swung a trifle to either the right or left side of the sole, thereby enabling the use of the pad and attached shell in either a right or left shoe 40 without the necessity of having right and left pads.

The pad is also moulded to cover the shell. In other words, the shell is moulded within 45 the pad so that the bottom side of the shell is covered with a skim coat 18 of rubber. This coat enables the shell to be better secured or cemented to the inner sole. It prevents the shell from deterioration or rust 50 and especially prevents the squeaking which sometimes occurs when there is any loose play between the shell and the inner sole, should the shell rust or should the leather with which it comes in contact get very dry.

The pad is also provided with a raised 55 tread surface 20 which, as will presently be explained, is a portion not covered by the cover or wrapping 4. The surface 20 is at that part of the pad which receives the direct pressure and frictional contact of the heel 60 and is raised with relation to the forward portion of the pad over which the cover extends, as will presently be explained, and also with relation to that portion of the pad surrounding the raised portion along the 65 sides and at the back of the pad lying adja-

cent the side and back edges thereof and over which the cover also extends. Leaving the surface of the raised portion of the pad exposed and uncovered makes a very smooth and soft tread surface. The raised portion 70 of the pad also provides positive means to spot the cover when applied so that it will in every instance have a precise application to the pad and inner sole to which it is secured.

The cover or wrapping 4 extends over the countersunk surface parts of the pad, that is, the parts thereof forward of the raised part 20 and also around the raised part along the sides and back. From its extension over the top surface of the pad, the cover is turned over and around the side edges of the pad with an extension beneath the sole, to which it is cemented or otherwise secured. The overlapping edge portions 21 of the cover 80 which are secured to the under side of the sole are preferably serrated or toothed in order that the edges of the cover may fit snugly to conform to the under surface of the sole without creasing, such serrating being especially desirable around the outer end of the sole. That part of the cover which laps by those portions of the pad which are backed by the shell, extends down alongside the edge 6 of the shell and beneath the adjacent edge portion of the inner sole, fitting snugly beneath said edge and all making a very snug and compact package at this point, which is to be desired.

That portion of the cover which extends by the forward edge 22 of the raised part 20 of the pad is provided with a cut-out wedge-shaped portion 23 which fits around a similarly wedge-shaped raised part 24 of the pad in extension of the part 20. This cut-out or V-shaped portion in the cover is for the purpose of preventing the cover from drawing taut and lifting the edge thereof away from the pad as might be the case if moisture caused the cover to shrink. The cut-out portion of the cover enables the cover to maintain its contact with the pad at this point even though the cover should have a tendency to contract by shrinkage.

The countersunk portion of the cover is countersunk in an amount substantially equal to the thickness of the fabric of which the cover is composed so that the exposed top surface of the raised parts 20, 24 of the pad will be substantially flush all around with the top surface of the cover.

Having thus fully described my invention, I claim and desire to secure by Letters Patent of the United States:—

1. An inner sole for a shoe having a dished heel portion, a dished shell fitting therein, said shell having a flattened, outturned marginal edge portion along the sides and back thereof with an adjacent edge portion of the sole underlying the same, a

resilient pad contained within the shell and having a cushion-forming marginal edge portion along the sides and back thereof resting upon and covering said outturned 5 marginal edge portion of the shell, and a cover fitting over the upper surface of the pad with extension over and around the edge of the pad, shell and underlying edge portion of the sole with attachment to the 10 under side of the sole.

2. An inner sole for a shoe having a dished heel portion, a dished shell fitting therein, said shell having an outturned marginal edge portion along the sides and back 15 thereof with an adjacent edge portion of the sole underlying the same, said shell having also a depressed front edge portion with flattened corner edges, a resilient pad contained within the shell and having a marginal edge portion along the sides and back 20 thereof resting upon said outturned marginal edge portion of the shell, said pad extending also over the depressed front edge portion of said shell and flattened corner 25 edges thereof, and a cover fitting over the upper surface of the pad with extension over and around the edge of the pad, shell and sole along the sides and back thereof 30 with attachment to the under side of the sole.

3. An inner sole for a shoe having a dished heel portion, a shell fitting therein having a dished body with a rounding back edge and substantially straight side edges, 35 the dished body of the shell having substantially the same inclination along the sides and back thereof at all points equidistant from the back and side edges of the shell, a resilient pad contained within said 40 shell, and a cover fitting over the upper surface of the pad with extension over and around the edge of the pad, shell and sole with attachment to the under side of the sole.

45 4. An inner sole for a shoe having a dished heel portion, a dished shell fitting therein, a thin coating of rubber between the shell and sole, a resilient pad contained within the shell, and a cover fitting over the upper surface of the pad with extension over and around the edge of the pad, shell 50 and sole with attachment to the under side of the sole.

5. An inner sole for a shoe having a

dished heel portion, a dished shell fitting 55 therein, a resilient pad of some plastic composition fitting within the shell with extension over and around the shell to form a skim coating on the back of the shell between it and the sole, and a cover fitting 60 over the upper surface of the pad with extension over and around the edge of the pad, shell and sole with attachment to the under side of the sole.

6. An inner sole for a shoe having a 65 dished heel portion, a dished shell fitting therein, a resilient pad fitting within the shell, said pad having a raised traction surface with countersunk surface portions of the pad lying outside the raised surface portion thereof, and a cover extending over the countersunk surface portions of the pad with extension over and around the edge of the pad, shell and sole with attachment to the 70 under side of the sole.

7. An inner sole for a shoe having a dished heel portion, a dished shell fitting therein, a resilient pad fitting within the shell, said pad having a raised tread surface portion with countersunk surface portions 75 lying forward of said raised portion with extension also around the same along the sides and back, and a cover fitting over the countersunk surface portions of the pad with extension over and around the edge of 80 the pad, shell and sole with attachment to the underside of the sole, the top surface of said cover being substantially flush with the raised tread surface of the pad.

8. An inner sole for a shoe having a 90 dished heel portion, a dished shell fitting therein, a resilient pad fitting within the shell, said pad having a raised tread surface portion with a substantially V-shaped extension from the forward edge thereof, said 95 pad having also a surface portion surrounding said raised portion and with extension forward thereof, a cover fitting over the countersunk surface portions of the pad with extension over and around the edge of 100 the pad, shell and sole with attachment to the under side of the sole, that portion of the cover extending by the front edge of said raised portion of the pad being provided with a substantially V-shaped cut-out 105 into which the V-shaped extension from the raised portion of the pad extends.

PHILIP C. STINGEL.
